BOMB RACK

Oliver L. Stockton, Manhattan Beach, Calif., as
signor to North American Aviation, Inc.

Application April 3, 1944, Serial No. 529,296

3 Claims. (Cl. 89—1.5)

1

This invention relates to improvements in bomb racks and has as its general object the provision of suitable means for the carrying and releasing of bombs as required in aircraft.

A more specific object of the invention is to provide an electrically operated bomb rack which is direct solenoid powered.

Another object of the invention is to provide a bomb release mechanism which is a complete unit requiring no external connections other than an electric socket.

Further objects of the invention are the provision of an electric bomb release mechanism which is adaptable to either a stationary installation as used on the underwing surface of a pursuit or attack ship, or which may be readily employed with the internal type racks used in the larger bombers. The present arrangement may be readily utilized in either of the foregoing installations, thereby providing improved interchangeability.

Still further objects of the invention are the provision of a bomb release mechanism which is compact, simple in construction, reliable and efficient in operation, having a minimum number of parts, and yet meeting all the requirements from the standpoint of usage.

In the drawings, like reference characters designate similar parts in the several views.

Fig. 1 is a schematic view illustrating primarily the arrangement of the relative parts of the bomb release mechanism embodying the invention.

Fig. 2 is a side elevation of a bomb rack embodying a slightly modified form of the same with a portion of the case broken away.

Fig. 3 is an end view of the unit shown in Fig. 2.

Fig. 4 is a plan view of a streamlined rack.

Fig. 5 is a side elevation of the same.

Fig. 6 is an end view of Fig. 5.

Fig. 7 is a side elevation of the rack with one-half of the case removed.

Fig. 8 is a wiring diagram, illustrating the electrical circuit included in the rack.

The embodiment of the invention shown in Fig. 1 comprises a pair of bomb-supporting hooks 1, 1', which are pivotally supported on the pins 2, 2'. The upper portions of the hook members are interconnected by a longitudinal link 3, being pivotally attached thereto at points 4, 4'. The link member may consist of a pair of parallel straps or bars in order to secure adequate strength, and a block 5, which serves as a catch, is secured between the links. The catch extends

2

below the link members, engaging a shoulder 6 on a trip-arm 7, which is pivotally mounted at 8, and carries a roller 9 at its opposite extremity. The roller rests on a trigger member 10, which is pivotally supported at 11 and has attached to its upper end a short link 12, the latter being connected to a rotary type solenoid 13 of the character shown, for example, in the United States Patent No. 1,283,151, issued on October 29, 1918, to Gledhill, and also in the United States Patent No. 2,347,369, issued on April 25, 1944, to Roters, by a lost motion connection comprising a pin 14 on the solenoid, and a slot in the link in which the pin 14 is engaged. The solenoid also carries an arm 15 which engages a recessed shoulder 16 on the trigger member 10.

The release of the bomb, supported on the hooks 1, is effected by energizing the rotary solenoid with an electrical impulse through a suitable releasing switch within the cockpit or bombardier's compartment. The armature of the rotary solenoid, when energized, turns in a clockwise direction. The initial movement of the armature raises the arm 15 from its locked position in engagement with the shoulder of the trigger member. The slotted portion of the link 12 provides for free rotation of the solenoid during this initial period. Pin 14 on the solenoid, upon reaching the limit of its travel in the slot, 20 draws the trigger member to the right, clearing the roller of the trip-arm 7. This arm is thus allowed to drop until it engages the stop 17, at which position it clears the catch 5 carried by the parallel links interconnecting the bomb-supporting hooks. Upon release of the catch, 25 the weight of the bomb suspended on the supporting hooks will be effective to move the link 3 to the right by virtue of the eccentricity between the points of support on the bomb hooks and the pivot points 2, 2' of the members. This eccentricity is also effective to overcome the action of spring 19 and urge arm 7 downwardly 30 against stop 17 when the trigger member is drawn to the right to clear the roller of trip-arm 7.

The mechanism is automatically recocked as follows: Upon hoisting a bomb into position, the supporting loops on the bomb will engage the projections 18, 18' on the hook members, forcing 35 the link 3 to the left against a spring 18a biasing the supporting hooks to bomb release position. Upon completion of this movement, and with the supporting loops of the bomb still forcing link 3 to the left, the trip-arm 7 is returned by 40 the spring 19 to engagement with the catch 5, 45

55 the spring 19 to engagement with the catch 5,

spring 20 returning the trigger to proper engagement with the roller 9, the spring 21 rotating the solenoid in a counter-clockwise direction to re-engage the arm 15 with the trigger member.

The foregoing mechanism is illustrated in a slightly modified form in Fig. 2 as adapted to a shackle of the type employed with the internal racks of bombers by the inclusion of appropriate supporting members 30, 30' having short horizontal pins 31, 31', intended for engagement with the shackle supporting hooks affixed to the side rails of the conventional type bomb rack. Such hooks may be as shown in the application of Charles J. Ulrich, Serial No. 528,189, filed March 27, 1944. Also shown is the provision of a transfer switch 32. The switch carries a pair of arms 33, 34, the first of which engages the stop pin 35, carried on the link 3. The two switch arms are inter-connected and lightly loaded by a torque spring 35a for clockwise rotation. Accordingly, upon release of the bomb and consequent movement of the pin 35 to the right, the arms 33 and 34 will rotate until the latter makes contact with the stop-pin 36 carried on the solenoid, which, when energized rotates to such a position as to form a stop to limit the travel of the switch arm 34. The arms are maintained in this position until the solenoid is de-energized by the release of the firing button in the pilot or bombardier's compartment. The arms 33 and 34 then rotate further under the pull of the torque spring until the arm 33 is stopped by the pin 35. The switch 32 is actuated thereby and functions to automatically route subsequent impulses (created upon actuation of the release switch by the pilot or bombardier) to the next successive bomb release unit.

The wiring diagram shown in Fig. 8 illustrates the manner in which the transfer switch is employed in the shackle circuit. When the jacks contained in the accumulator socket 41 are properly engaged, the lead 40 is conducted through the accumulator socket to the transfer switch 32. When the switch is in normal position as shown, the impulse from the firing button will energize the release solenoid 13, the circuit being completed through the lead 42 which forms a common ground. Upon completion of the release of the bomb from the rack, the transfer switch is mechanically actuated to contact the lead 43, thus disconnecting the solenoid 13 from the circuit, so that subsequent impulses will not affect the new setting of the switch 32, and such subsequent impulses are therefore conducted to the next unit in the system. The other portions of the wiring diagram indicate the nose and tail fuse control (arming) units 44 and 45, and their respective leads. These are standard units, usual and well known by those versed in the art.

Also shown is a by-pass switch 46 which consists of a mechanical arrangement whereby upon disconnecting any individual shackle a contact is automatically made within the socket, thereby passing over the station wherein the jacks are thus disconnected. By this means the impulses from the firing button are transferred to the next active station. Such an arrangement is necessitated in racks provided for the carrying of either large or small bombs, since space and weight limitations would preclude the possibility of loading all of the stations with the larger size bombs. By this means each successive impulse reaches the next loaded station regardless of the loading sequence in rack.

A further modification of the subject mechanism is also shown in Fig. 4 as developed in a streamlined version primarily for external installations on high speed ships. Such an arrangement would be particularly applicable to the wing-racks of pursuit or attack ships, wherein the absolute minimum of drag is permissible. The present arrangement providing as it does, an extremely compact unit having a minimum of frontal area as viewed from the end, (Fig. 6) is suitable for such purposes. Suitable hangers forming a portion of the structure of the ship, are intended for attachment of the racks by means of bolts passing through the pairs of sleeves 50, 50', provided in the case 51 adjacent to the opposite ends of the rack. The accumulator socket 41 accommodates all of the necessary electrical connections to provide for satisfactory operation of the racks. The unit shown, however, may be readily used for internal racks by providing suitable hanger members similar to those shown in the previous modification, which may also be attached by bolts or pins through the sleeves provided. This arrangement allows for complete interchangeability on various installations.

I claim:

1. A bomb shackle comprising a support, a pair of bomb-supporting hooks pivoted thereon and adapted for movement to bomb-releasing position by the weight of the bomb supported thereby, means inter-connecting said hooks for movement in unison, latching means cooperating with said inter-connecting means and spring biased toward a position latching said hooks in bomb-supporting positions, a solenoid having an armature, means carried by said armature adapted in the de-energized position thereof to coat with said latching means to lock the latter against unlatching movement, and means having a lost-motion connection with said solenoid first permitting said locking means to release said latching means and then operating upon said latching means to release the latter for unlatching said bomb-supporting hooks.

2. A bomb shackle comprising a support, a pair of bomb-supporting hooks pivoted thereon and adapted for movement to bomb-releasing position by the weight of the bomb supported thereby, means inter-connecting said hooks for movement in unison, latching means cooperating with said inter-connecting means and spring biased toward a position latching said hooks in bomb-supporting positions, a solenoid having an armature, means carried by said armature adapted in the de-energized position thereof to coat with said latching means to lock the latter against unlatching movement, energizing means, and a transfer switch adapted in a first position to route energy from said latter means to said solenoid and in a second position to route energy from said energizing means to another bomb shackle, said transfer switch having means cooperating with said inter-connecting means and with said solenoid whereby it is restrained in its first position until the bomb-supporting hooks have moved to releasing position and the solenoid has moved from its energized position back to its de-energized position.

3. A bomb shackle comprising a support, a pair of bomb-supporting hooks pivoted thereon and adapted to move to bomb-releasing positions under the weight of the bomb supported thereby, means inter-connecting said hooks for movement in unison, a trip-arm pivoted to said sup-

port and spring urged to a position wherein it is adapted to latch said hooks in bomb-supporting positions, a trigger coacting with the end of said trip-arm remote from its pivot and spring urged to a position in which it holds said trip-arm in latching position, a solenoid carrying a locking element adapted in the de-energized position of the solenoid to coact with said trigger for locking the same in its holding position, a lost-motion connection between said armature and said trigger adapted upon energization of the solenoid to first permit said locking element to move away from its locking position and then to move said trigger away from its holding position, energizing means, a transfer switch adapted in a first position to conduct energy from said means to said solenoid and in a second position to disconnect said solenoid from said energizing means and to route the energy from said energizing means to the solenoid of a second shackle, said transfer switch having a pair of control arms, one of which cooperates with said inter-connecting means to restrain said transfer switch in said first position.

tion when the bomb-supporting hooks are in bomb-supporting position and a projection carried by said rotary armature adapted when the solenoid is energized to move to a position coacting with the other arm of said transfer switch for restraining said transfer switch in said first position until said solenoid has returned to its de-energized position.
